UNITED STATES PATENT OFFICE

RALPH R. TEETOR, OF HAGERSTOWN, INDIANA

DESIGN FOR A FISHING-POLE HANDLE

Application filed November 17, 1930. Serial No. 37,693. Term of patent 14 years.

To all whom it may concern:

Be it known that I, RALPH R. TEETOR, a citizen of the United States, residing at Hagerstown, in the county of Wayne, State of Indiana, have invented a new, original, and ornamental Design for Fishing-Pole Handle, of which the following is a specification, reference being had to the accompanying drawing, forming a part hereof, wherein. The figure is a view of the article in perspective, showing my new design.

I claim:

The ornamental design for a fishing pole handle, as shown.

RALPH R. TEETOR.
